UNITED STATES PATENT OFFICE.

CLIFFORD R. DUMBLE, OF ARLINGTON, MASSACHUSETTS, ASSIGNOR, BY MESNE ASSIGNMENTS, TO THE LAMSON COMPANY, OF BOSTON, MASSACHUSETTS, A CORPORATION OF MASSACHUSETTS.

REMOVABLE LABEL FOR CARRIERS.

Application filed June 7, 1921. Serial No. 475,588.

To all whom it may concern:

Be it known that I, CLIFFORD R. DUMBLE, citizen of the United States of America, and resident of Arlington, in the county of Middlesex and State of Massachusetts, have invented new and useful Improvements in Removable Labels for Carriers, of which the following is a specification.

In pneumatic carrier systems of the kind employing carriers which are transmitted through pneumatic tubes, it is customary to apply identification numbers or other characters or marks to the several carriers to indicate particular stations or routes in the system to which the several carriers belong, or to indicate particular classes of transactions for which the carriers are used. When the identifying mark or index is permanently affixed, as by stamping it on the carrier, as has heretofore been the practice, a change of marking or indexing cannot readily be made. It is often desirable to be able to change the identifying marks when the carriers are to be used at different stations, or for different kinds of transactions, or for other reasons, and the principal object of the present invention is to provide a removable and replaceable identification label for carriers of the kind referred to, which can be readily applied and removed, and which will not interfere with the opening or closing of the carrier nor with the transit thereof through the pneumatic tubes.

In the accompanying drawings which illustrate the invention embodied in a carrier of a well known type for use in pneumatic carrier systems,—

Fig. 1 is a front elevation showing the carrier closed;

Fig. 2 is a front elevation showing the carrier open;

Fig. 3 is a section on line 3—3 of Fig. 1; and

Fig. 4 is a plan view of the identification label removed from the carrier.

The carrier herein shown consists of an inner cylindrical casing 1 and an outer cylindrical casing 2, the former being closely fitted within the latter, and the two casings being adapted for limited, relative, rotary movement. The inner casing 1 is connected to one of the felt covered heads 3, and the outer casing 2 is connected to the other felt covered head 4, so that by grasping the

heads 3 and 4, one with each hand, the casings may be turned relatively to each other to open and close the carrier.

The inner casing 1 is provided with an opening 5 and the outer casing 2 is provided with a similar opening 6. These openings are out of alinement when the carrier is closed as shown in Fig. 1, but are adapted to be brought into register with each other to open the carrier, as shown in Fig. 2, when the two casings are relatively rotated. There are suitable stops (not shown) for limiting the relative movement of the casings in each direction. The parts thus far described may be of usual construction, and in and of themselves do not constitute the present invention.

A second aperture 9 is provided in that part of the wall of the inner casing 1 which closes the opening 6 of the outer casing, and whose outer surface 7 is exposed through the opening 6 when the carrier is closed and is concealed by the outer casing when the carrier is open.

A label 8 of paper, sheet celluloid or other suitable material, is removably secured to the inner casing over the aperture 9, so that one side of the label will be visible through the opening 6 in the outer casing, when the carrier is closed, the label then appearing on the outside of the carrier, and the other side of the label will be visible through both openings 5 and 6 of the inner and outer casings respectively when the carrier is open, the label then appearing on the inside of the carrier. Thus a single removable label may be employed which is visible when the carrier is either open or closed. It will be understood that the label will bear the same identifying numerals or other characters on both sides.

The label, being carried by the inner casing, will not interfere in any way with the transit of the carrier through the tubes, and is visible through the common opening 6 whether the carrier is open or closed.

The means employed for holding the label in position should also be such as to make easy its insertion and removal, and such as not to interfere with the opening and closing of the carrier. To this end the aperture 9 is formed in a depressed portion 14 of the wall of the inner casing 1, so that when the label 8 lies in the depression and extends

across the opening 9, its outer face will be substantially flush with or slightly below the cylindrical surface of the casing 1. Thus the label will present no salient or projecting parts to interfere with the turning of the inner casing in the outer casing when the carrier is opened. At opposite edges of the depressed area 14 are a pair of slots 10 and 11 formed in the walls of the inner casing, 5 through which the ends of the label 8 project; and accidental displacement of the label is prevented by stops 12 and 13, which may be struck up from the metal of the inner casing, to engage the ends of the label. 10

15 The label 8 being made preferably of sheet celluloid or the like, possesses sufficient inherent resiliency so that it will be yieldingly but removably held in position when applied to the carrier and bent to 20 conform substantially to the curvature of the carrier wall as shown in Figure 3.

I claim:

1. A carrier comprising relatively movable inner and outer casings having openings adapted to be moved into and out of alignment by the relative movement of the casings in opening and closing the carrier, and means whereby an indicator label may be removably secured to the wall of one of 30 said casings.

2. A carrier comprising relatively movable inner and outer casings having openings adapted to be moved into and out of alignment by the relative movement of the 35 casings in opening and closing the carrier, and an indicator label removably secured to the inner casing, the parts being so arranged that the label will be visible both from the exterior and the interior of the carrier.

40 3. A carrier comprising relatively movable inner and outer casings having openings therein, and an indicator label removably secured to the inner casing and arranged so as to be visible through an opening in 45 the outer casing when the carrier is in either open or closed position.

4. A carrier comprising relatively movable inner and outer casings having openings adapted to be moved into and out of alignment by the relative movement of the casings in opening and closing the carrier, and an indicator label removably secured to the inner casing in a position to be visible through the opening of the outer casing 55 when the carrier is closed, and through the openings of both the inner and outer casings when the carrier is open.

5. A carrier comprising relatively movable inner and outer casings having openings 60 adapted to be moved into and out of alignment by the relative movement of the casings in opening and closing the carrier, and the inner casing having a second aperture in that part of its wall whose outer surface is exposed through the opening in the outer cas-

ing when the carrier is closed and is concealed by the wall of the outer casing when the carrier is open, and a label removably secured to the inner casing over the second aperture, whereby one side of the label will 70 be visible through the opening in the outer casing when the carrier is closed, and the other side will be visible through the openings of both the outer and inner casings when the carrier is open. 75

6. A carrier comprising relatively movable inner and outer casings, a depression in the wall of the inner casing, and a label removably mounted in said depression and lying wholly below the outer surface of the 80 wall of the inner casing.

7. A carrier comprising relatively movable inner and outer casings, a depression in the wall of the inner casing, having an aperture therein, and a label removably 85 mounted in said depression visible from both sides of said inner casing wall, and lying wholly below the outer surface of the wall of the inner casing.

8. A carrier comprising relatively movable inner and outer casings, a depression in the wall of the inner casing having an aperture therein and a pair of slots, one at each side of the aperture, and a label removably mounted in said depression with its opposite 95 edges engaging said slots.

9. A carrier comprising relatively movable inner and outer casings, a depression in the wall of the inner casing having an aperture therein and a pair of slots, one at each 100 side of the aperture, and a label removably mounted in said depression with its opposite edges engaging said slots, and stops to prevent the displacement of said label when in position. 105

10. A carrier comprising a shell-like casing having an inwardly depressed portion provided with an opening in its bottom wall, and having a slot at each side of the depression, a label provided with indicia upon 110 its opposite faces removably mounted in said depression with its opposite margins extending through the respective slots, and stops at the remote sides of the slots constructed and arranged to engage the edges of the 115 label.

11. A carrier comprising a cylindrical casing having an inwardly depressed portion provided with an opening therethrough, a label seated within said depression, and 120 means for preventing accidental displacement of the label therefrom.

12. In combination, a wall having a depression, a pair of slots one at each side of the depression, a label removably mounted 125 in said depression with its opposite margins extending through said slots, and stops at the sides of the slots to engage the edges of the label to prevent the displacement of said label when in position. 130

13. A carrier having relatively movable inner and outer casings having openings adapted to be moved into and out of alignment by the relative movement of the casings in opening and closing the carrier, and means whereby an indicator label may be removably secured to the wall of the inner casing. 5
14. A carrier having relatively movable inner and outer casings having openings adapted to be moved into and out of alignment by the relative movement of the casings in opening and closing the carrier, and an indicator label removably secured to the 10 wall of the inner casing in such position that its outer surface will be exposed through the opening of the outer casing when the carrier is closed and will be covered by the outer casing when the carrier is open. 15
15. A carrier having relatively movable inner and outer casings closely fitting each other and a label removably mounted on the wall of the inner casing with its outer sur- 20
- face within the peripheral plane of the outer surface of the inner casing, whereby the label will not interfere with the opening or closing of the carrier. 25
16. A carrier comprising relatively movable inner and outer casings of sheet material closely fitting each other, the inner casing 30 having a portion thereof struck inwardly to provide a depressed area, a label seated within such depressed area, and means whereby such label is retained against accidental removal therefrom. 35
17. A carrier comprising an inner cylindrically curved member having a depression therein, the longitudinal edges of the bottom of said depression being defined by elongate slots, a curved label seated within said depression with its opposite edges engaging the respective slots, and means to prevent circumferential displacement of the label. 40

Signed by me at Boston, Massachusetts this twenty-fourth day of May 1921.

CLIFFORD R. DUMBLE.
